UNITED STATES PATENT OFFICE.

JOSEPH T. HOMAN, OF CINCINNATI, OHIO.

DESIGN FOR A SPOON-CUP.

SPECIFICATION forming part of Design No. 26,972, dated April 27, 1897.

Application filed March 12, 1897. Serial No. 627,253. Term of patent 14 years.

To all whom it may concern:

Be it known that I, JOSEPH T. HOMAN, a citizen of the United States, residing at Cincinnati, in the county of Hamilton and State of Ohio, have invented and produced a new and original Design for a Spoon-Cup; and I do hereby declare the following to be a full, clear, and exact description of the same, reference being had to the accompanying drawings, which form a part of this specification.

My invention comprises a design for a spoon-cup to be used by the Catholic clergy in visiting the sick, the special features of said design being shown in the annexed drawings,

5 wherein—

Figure 1 is a plan of said spoon-cup, and Fig. 2 is a vertical section of the same.

The bottom A of this spoon-cup is flat and oval-shaped, and from this bottom the sides

of the vessel flare upwardly and outwardly, 20 as at B, the front end of said vessel being formed into a spout C, that facilitates pouring. Projecting from the rear end of this spoon-cup is a curved handle D, the upper surface of which has a marginal bead or molding E, 25 inclosing a cross F, surrounded by wreaths of wheat G and grape-vines H. I is a ribbon or bow uniting the stems of these wreaths.

I claim as my invention—

The design for a spoon-cup, as herein shown 30 and described.

In testimony whereof I affix my signature in presence of two witnesses.

JOSEPH T. HOMAN.

Witnesses:

JAMES H. LAYMAN,
JOHN C. ROGERS.
